His Attorneys.

UNITED STATES PATENT OFFICE.

MAX R. LEHMAN, OF QUINCY, ILLINOIS, ASSIGNOR TO ORBON STOVE CO., OF BELLEVILLE, ILLINOIS, A CORPORATION OF ILLINOIS.

DESIGN FOR A HEATER.

Application filed March 30, 1927. Serial No. 21,402. Term of patent 14 years.

To all whom it may concern:

Be it known that I, MAX R. LEHMAN, a citizen of the United States, residing at Quincy, county of Adams, and State of Illinois, have invented a new, original, and ornamental Design for Heaters, substantially as shown in the accompanying drawing, in which—

Fig. 1 is a perspective view showing my

new design for heater with the doors of the heater cabinet closed.

Fig. 2 is a similar perspective view with the doors of the cabinet open.

I claim:

The ornamental design for a heater, substantially as shown.

MAX R. LEHMAN.
